ATTORNEY

UNITED STATES PATENT OFFICE.

RAYMOND M. GUY, OF WINFIELD, KANSAS, ASSIGNOR TO GUY AUTO HUB LOCK COMPANY, OF WINFIELD, KANSAS, A CORPORATION.

DESIGN FOR AN AUTOMOBILE-WHEEL-HUB CAP.

57,643.

Specification for Design.

Patented Apr. 26, 1921.

Application filed February 24, 1920. Serial No. 361,006. Term of patent 7 years.

To all whom it may concern:

Be it known that I, RAYMOND M. GUY, a citizen of the United States, residing at Winfield, in the county of Cowley and State of Kansas, have invented a new, original, and ornamental Design for an Automobile-Wheel-Hub Cap, of which the following is a specification, reference being had to the accompanying drawings, forming a part thereof.

Figure 1 is a plan view of my hub cap design.

Fig. 2 is a side view of same, the dotted lines show the position of a wheel.

I claim:—

The ornamental design for an automobile wheel hub cap, as shown.

RAYMOND M. GUY.

Witnesses:

W. A. NETHERCOT,
Mrs. R. M. CHARLES.
